UNITED STATES PATENT OFFICE

DELBERT J. MARTIN, OF SACRAMENTO, CALIFORNIA

PERMANENT WAVING ROD

Application filed April 7, 1930. Serial No. 442,162.

This invention relates to devices for use in connection with the permanent waving of hair. The individual locks of hair before being subjected to heat are wrapped about waving rods. There are two forms of wrap now in general use. One is called the croquignole wrap and the other the spiral wrap. The croquignole wrap, which is taken from the ends of the hair toward the scalp, gives tight curled ends and relatively loose curls or waves toward the scalp. The spiral wrap gives practically the reverse arrangement.

The croquignole wrap is preferred by customers as a general rule on account of the relatively tight curls formed on the ends of the hair, but with the longer hair now being worn the wave is too loose toward the scalp. To provide a wave of a more or less tightly curled or uniform nature from end to end however now necessitates the use of two separate rods, one especially designed for the croquignole and the other for the spiral wave. The operation necessary to attain the desired end therefore consumes considerable time, which is irksome to the patient and necessitates the operator working at a very small profit or even at a loss, or having to charge a price which many are not inclined or are unable to pay.

The principal object of my invention is to avoid the above time-taking and expensive features of operation by providing a single rod so constructed that both the croquignole and spiral wraps may be made thereon, in a continuous operation and in a very short time. The two separate rods and the corresponding sets of operations now necessary are therefore combined in one, with a consequent reduction in time and also expense for equipment.

A further object of the invention is to provide a rod for the purpose so constructed that no tying of the hair or the wrapping flannel subsequently used is necessary, thus further simplifying operations and cutting down the time consumed in the waving of the hair. My improved rod is also constructed so that it may be used in connection with any standard tubular heating coil such as now commonly used in connection with waving rods.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved rod.

Fig. 2 is a sectional elevation of the same.

Figs. 3 to 5 are side elevations of the rod showing the initial engagement of the hair, the croquignole wrap and the spiral wrap respectively.

Fig. 6 is a side elevation of the rod showing the wrapped hair as surrounded by the protecting flannel.

Referring now more particularly to the characters of reference on the drawings, the rod as a whole comprises a pair of tubular sections 1 and 2, which are long and short respectively and are longitudinally aligned with each other so as to form a single unit. The sections have a continuous shallow taper from the outer end of the rod 1 which terminates in a curved flare as at 3 in the outer end of the section 2. The sections are turnably mounted in connection with each other and means is provided to resist such turning. This means as shown comprises a cylindrical block 4 secured in and projecting from the end of the section 1 adjacent the section 2, and extending into said section 2. The section 2 has a similar block 5 secured therein and engaging the adjacent end of the block 4; the engaging ends of the blocks having symmetically shaped and cooperating ratchet teeth 6. A headed screw 7 is secured in the block 4 and projects freely through the block 5 to adjacent the outer end of the section 2; a compression spring 8 being disposed between the head of the screw and the block 5. This arrangement normally holds the sections in close engagement with each other, while permitting of their rotation relative to each other in either direction, if suffi-

ciently to overcome the resistance of the ratchet teeth 6.

cient rotative pressure is applied to overcome the resistance of the spring so as to permit the teeth 6 disengaging and passing by each other.

5 Slidably mounted on the outer small end of the section 1 and frictionally engaging the same is a spring saddle 9 from which a spring strip 10 projects lengthwise of the rod toward the opposite end of the same; this strip forming an acute angle with the adjacent surface of the rod as plainly shown and being convexly curved relative to the rod so that it may lie closely thereagainst. This strip with the adjacent portion of the rod forms 10 a spring clip or wedge-like recess for initial clamping engagement with the hair, as shown in Fig. 3. Formed on the saddle is another relatively short spring strip 11 which extends in the same direction as the strip 10, and also forms with the adjacent portion of 15 the saddle a spring clip for a purpose which will be seen later.

Secured at one end to the section 2 toward the outer end of the same is a spring-clip strip 12 which extends thence spirally along 20 the section 2 with a left-hand pitch and in slightly diverging relation to the rod, to a termination a short distance beyond the adjacent end of the section 1, or in overlapping relation thereto. Adjacent such termination the strip 12 is formed with a decided outward bend or curve, as shown at 12a, which facilitates the passing of the hair between said strip and the rod.

25 35 In operation the rod is held in the fingers of the operator so that the clip 10 is toward the right and the lock of hair 13 to be raised is passed adjacent its end under the clip so that it is wedgingly clamped against the rod, as shown in Fig. 3. The rod is then turned 40 with a left hand movement so as to wrap the hair about the rod and clip 10 a desired number of times with a more or less straight or croquignole form of wrap, as shown in Fig. 4. The rod is then angled somewhat, while 45 its rotation is continued, so that the hair will then be raised about the rod with a decided spiral as shown in Fig. 5.

The tapering of the rod prevents any slack 50 developing in the hair toward its relatively advanced edge as it is thus wrapped spirally. When the wrap reaches the section 2 or the clip 12 (by which time the rod is close to the scalp) the section 2 is rotated relative to the section 1 so as to cause said clip to engage the hair as shown in Fig. 5. The section 1 is then turned relative to the section 2, which causes the wrappings to be tightened up 55 about the rod from end to end to any desired extent.

The usual flannel strap 14 is then raised 60 about the hair on the rod, from the section 2 toward the section 1; the free end of this strip or that adjacent the outer end of the 65 section 1 being then passed under and caught

by the clip 11. This avoids the necessity of tying the flannel against unwrapping as must now be done, and which of course in the aggregate consumes considerable time. The rod is now in condition to be inserted in the 70 usual type of tubular heating coil, the size of the rod being such that it will fit any standard coils of this type.

When the operation is completed the flannel is of course first removed and the clip 12 75 is then disengaged from the hair by turning the section 1 in a forward or right hand direction while holding the section 2 stationary. This action automatically clears said clip from the hair without any pulling on the 80 same or disturbing of the wrap or curl being necessary.

The provision of the flare 3 on the outer end of the section 2 prevents the hair from possibly passing over the adjacent end of the 85 rod. The saddle 9 being slidable on the rod it may be adjusted in position according to the length of the hair to be wrapped, an operation which may be easily performed with the proper judgment after a little experience.

90 From the foregoing description it will be readily seen that I have produced such a device as substantially fulfills the objects of the invention as set forth herein.

95 While this specification sets forth in detail the present and preferred construction of the device, still in practice such deviations from such detail may be resorted to as do not form a departure from the spirit of the invention, as defined by the appended claims.

100 Having thus described my invention what I claim as new and useful and desire to secure by Letters Patent is:

1. A permanent waving rod comprising a 105 rod member, and a spring element projecting lengthwise thereof from adjacent one end thereof, and arranged to provide with the adjacent surface of the rod, a wedge-like recess for clamping engagement with the hair.

2. A permanent waving rod comprising a 110 rod member, a spring element projecting lengthwise thereof from adjacent one end thereof, and arranged to provide with the adjacent surface of the rod a wedge-like recess for clamping engagement with the hair, and 115 means supporting the element from the rod for sliding movement along the same.

3. A permanent waving rod comprising a 120 rod member, means on the rod for clamping engagement with the hair, and separate means on said rod adjacent said first named means for clamping engagement with one end of a fabric wrapping.

4. A permanent waving rod comprising a 125 rod member, a spring strip projecting lengthwise thereof from adjacent one end of the same and forming an acute angle with the rod, and another spring strip similarly disposed relative to the rod but nearer said end of the rod than the first named strip.

5. A permanent waving rod comprising longitudinally alined rod sections turnable relative to each other, means between the sections resisting such turning, means mounted on one rod section toward the outer end of the same for clamping engagement with the hair adjacent its ends, and means fixed on the other rod section for clamping engagement with the adjacent portion of the hair after it has been wrapped on the rod from the other end thereof.
- 10

6. A permanent waving rod comprising longitudinally alined rod sections turnable relative to each other, means between the sections resisting such turning, means on one rod section toward the outer end of the same for clamping engagement with the hair adjacent its ends, and a spring strip secured at one end to the other rod section and adjacent the outer end thereof and extending thence along said section in spiral and gradually diverging relation thereto for clamping engagement with the hair adjacent the scalp.
